UNITED STATES PATENT OFFICE.

REUBEN NOEL PERLEY, OF STONEHAM, MASSACHUSETTS.

SHAPE AND STRUCTURE OF SUBMARINES, MOBILE TORPEDOES, OR EXPLOSIVE CARRIERS.

Application filed August 22, 1921. Serial No. 494,243.

To all whom it may concern:

Be it known that I, REUBEN NOEL PERLEY, a citizen of the United States of America, residing at Stoneham, in the county of Middlesex and State of Massachusetts, have invented certain new and useful Improvements in Shape and Structure of Submarines, Mobile Torpedoes, or Explosive Carriers, of which the following is a specification.

10 This invention relates in general to a certain new and useful improvement in the shape and structure of submarines, mobile torpedoes, or explosive carriers, and more particularly to the combination of a main 15 hull or spindle of any suitable shape which is entirely submerged and surmounted by a hydroplane float or vane to which it is connected by a streamline superstructure. The main hull when in its best operative position 20 is located at a predetermined distance beneath the surface of the water and contains, or may contain, the usual engines and propelling and auxiliary mechanisms, personnel, fuel, ballast, explosive, fixtures, accessories, and supplies. The streamlined 25 connecting superstructure may contain companion ways, ducts for the air supply of the power plant or for ventilation of the interior of the hull, or ducts to provide outlet 30 for the exhaust gases. The hydroplane float or vane which is on or near the water surface may contain suitable air inlets, air-water separators, control and observation compartments or all of these features and 35 others.

It is necessary for such vessels as mentioned above, to be able to maintain a straight course, not unduly disturbed by exterior forces so that while subject to their 40 own forces of propulsion they will follow a constant rectilinear course on the axis of the vessel, or in other words there must exist an equilibrium of intensity and direction between the resisting forces of the water and 45 the force of propulsion. It is well known in naval architecture that this equilibrium is best obtained in the case when the resultant of the resistance of the water meets with the resultant of the forces of propulsion 50 much to the stern of the line which unites the center of gravity with the center of buoyancy. To obtain this object torpedoes and submarines, and other submersibles, having spindle shape and other hulls, have 55 been provided at their extreme stern with

horizontal surfaces which in the case of the boat tending to deviate from the direction of course tend to automatically right her by creating strong resistance at the stern to this deviation.

It is well known in naval architecture that the length-draft-ratio is the quotient of the length in feet, divided by the draft in feet. It is also well known in naval architecture 60 that the speed-length-ratio is the quotient of the speed in knots divided by the square root of the length in feet.

It is well known in naval architecture that there is a certain practical limit in the ratio of the length to the maximum diameter 65 of such a spindle below which the spindle becomes unstable directionally. Furthermore, as is well known, there exist practical limits as to the ratio of the speed of propulsion of such a craft to the square root 70 of its length, beyond which it has heretofore been impossible to go without instability.

Furthermore, it is well known in naval architecture that at a range of speed length ratios, generally between 1.2 and 2, the 75 stern of a submerged spindle near the surface shows a marked tendency to rise and the bow a marked tendency to depress as a result of the streamline forces of the water wave generated by the shape itself.

It is an object of my invention to provide means whereby the above mentioned normal limits may be greatly exceeded in the design of the spindle and the velocity which it is to obtain, by providing the necessary spindle 80 or hull, and mounting upon the same, by suitable connecting superstructure, a hydroplane float or vane. This hydroplane float or vane is adapted to act to assist in maintaining the main hull at a fixed average 85 depth below the water surface. The resultant depth regulation, or proximity to the surface, is inherent to the shape in the design of the spindle and superstructure and their relative positions, and may be desired 90 for the purposes of observation, assurance of air supply, safety or for other purposes, in addition to that of maintaining the main hull directionally stable.

This invention relates more particularly 105 to the shape, extent and design of the hydroplane or vane which may contain enough reserve buoyancy so distributed longitudinally and laterally, either by itself or in conjunction with other superstructures and 110

hydroplanes or vanes, as to provide at moderate speeds sufficient righting moments to restrict within safe limits the tendency to dive, which characterizes all spindles 5 moving near the surface of the water when at speeds resulting in speed length ratios between 1.2 and 2. The hydroplane, or vane, comprises overhanging surfaces adapted to bear upon the water as needed, which 10 are of such longitudinal or lateral inclinations or ranges of inclinations as to provide at all high speeds sufficient righting moments to restrict within safe limits the tendency to dive; the division between 15 moderate and high speeds to be considered as those points at which static forces, such as gravity and the force of buoyancy, give way in relative importance to the streamline or dynamic forces at speeds ordinarily referred to as planing speeds.

More specifically this invention relates to an essentially submerged structure designed to meet the conditions of deep draft with short length or of high speed with short 25 length, as mentioned above, or to length draft ratios smaller than 6 for example and to speed length ratios greater than 1.2, and more specifically as to those two abnormal characteristics taken together. In its specific 30 form this connecting superstructure is to be streamlined and is adapted to have horizontal sections patterned after the U. S. Navy Standard Strut Section and in its best form spreads at its base for the advantage of 35 strength where it is attached to the main hull. The upper portion of the connecting superstructure blends into the shape of the hydroplane or vanes, so that the blunt nose of the superstructure is provided with a 40 sharper entrance in the vicinity of the load water line.

Various other objects of my invention will appear in the accompanying specification and claims and will be disclosed in the accompanying drawings, in which:

Figure 1 is a side elevation in perspective of my device;

Figure 2 is an enlarged elevation of the fore part of the device showing in detail the 50 superstructure and the hydroplane float;

Figure 3 is a front elevation of my device; and

Figure 4 is a characteristic attitude chart showing movements of bow and stern of 55 model, and shows clearly the positions between speed length ratios 1 and 2 of my device.

Figure 5 is a characteristic attitude chart showing vertical movements of bow and 60 stern of models lacking certain special features which my device provide and is shown for contrast.

Referring to the drawings in detail, A is the main hull or spindle, of any suitable 65 shape, preferably that of the usual stream-

line spindle; B is a superstructure, which is streamlined with reference to the water through which the spindle is moving, and provides means for connecting the spindle A with the hydroplane float C. This connecting superstructure B may, as hereinbefore discussed, provide companion ways, air ducts and the like, between hydroplane float C and the spindle A. The hydroplane float C is designed to provide suitable buoyancy 70 by reason of its action as a float and is to be so designed from a structural point of view as to provide a planing effect on the surface of the water, through which the spindle is moving, in the eventuality of the bow depressing; C, as shown in Figs. 2 and 3, is provided with surfaces inclining laterally and forwardly in such a way as to provide the maximum stabilizing effect against any tendency of the spindle toward lateral movement or longitudinal or directional variation as in the case of diving and the like.

The hydroplane float C is provided, as shown, with a sharp entering edge for cutting the water as necessary. The superstructure B is so designed that its surface will, without any abrupt angles, effect the configuration of the base of the hydroplane float. The lower portion of the superstructure B is widened somewhat at the base, and 90 is adapted also to be provided with a portion which approaches the configuration of the spindle without any abrupt angles.

If desired, additional minor superstructure and floats, such as B' and C', may be 100 provided without departing from the spirit of my invention. The hydroplane, or vane, if desired, need not provide reserve buoyancy.

Figure 2 shows an enlargement of the hydroplane float showing the overhanging or bearing surface of the hydroplane with a range of longitudinal slopes or inclinations from the horizontal covering all suitable angles, thus providing a favorable angle to the 105 water surface for producing lifting forces where the craft is inclined at an angle of pitch, the lateral slope or overhanging being sufficient to prevent excessive pounding of the waves and providing adequate lateral 110 righting means to prevent undue transverse inclination, the sharp wedge bow providing a sharp entrance in order to divide the water as the hydroplane passes through.

It has been discovered that the optimum 120 depth of operation of such devices as is herein disclosed is not less than that of one half the diameter of the spindle. Numerous experiments embodying my invention, as shown with this provision, makes possible speed 125 length ratios above 1.2 and length draft ratios much lower than 6. Numerous shapes, essentially submerged, proved unstable under test conditions between speed length ratios of 1.2 and 2 as shown in the chart 130

of Figure 5 to the extent that they had to be supported until a greater (or less) speed had been attained, a condition corrected by my device as indicated clearly in chart of Figure 4.

The same experiments disclosed special merit in the combination where superstructures and hydroplane floats were positioned at the extremities of the spindle, thereby concentrating the lifting force of buoyancy or the dynamic lifting force of the hydroplane floats where their righting arms were a maximum.

I claim:

15 1. A marine structure comprising in combination a submerged main hull, a streamline superstructure surmounting the hull and a hydroplane float constituting a continuation of the superstructure and shaped to 20 produce righting moments of sufficient intensity to counteract the dynamic forces effective at planing speeds.

25 2. A marine structure comprising in combination a submerged hull and a surmounting streamline superstructure terminating in a hydroplane float, the water contacting surfaces of the float being in such angular relation with respect to the surface of the water as to produce righting moments of sufficient 30 intensity to counteract the dynamic forces effective at planing speeds.

35 3. A marine structure comprising in combination a submerged hull and a streamline superstructure surmounting the hull and terminating in a surface hydroplane float, the latter projecting above water level and having its water contacting surfaces in such angular relation with respect to the water surface as to produce righting moments of 40 sufficient intensity to counteract the dynamic forces effective at planing speeds.

45 4. A marine structure comprising in combination a submerged hull, a streamline superstructure surmounting the hull and terminating in a partially submerged hydroplane float, having overhanging surfaces at such angular relation with respect to the water surface as to produce righting moments of sufficient intensity to counteract the 50 dynamic forces effective at planing speeds.

55 5. A marine structure comprising in combination a submerged hull, a streamline superstructure surmounting the hull and terminating in a partially submerged hydroplane float, the latter having overhanging water bearing surfaces of such lateral and longitudinal inclination as to produce righting moments of sufficient intensity to counteract the dynamic forces effective at planing 60 speeds.

65 6. A marine structure comprising in combination a submerged hull, a surmounting streamline structure and a hydroplane float, the lines of the streamline structure merging into those of the hull and float, said float

having overhanging surfaces, so inclined with respect to the surface of the water as to produce at planing speeds righting moments of sufficient intensity to overcome the dynamic forces effective at such speeds.

70

7. A marine structure comprising a submerged hull, a surmounting streamline superstructure and a hydroplane float integral with the superstructure, the lines of the superstructure merging into those of the float 75 and hull, said float being formed with overhanging surfaces so inclined with respect to the surface of the water as to produce at planing speeds righting moments of sufficient intensity to counteract the dynamic forces effective at such speeds.

8. A marine structure comprising in combination a hull, submerged to a predetermined depth, a streamline superstructure surmounting the hull and a hydroplane float 85 integral with the superstructure and projecting well above water level, the lines of the superstructure merging into those of the float and hull, said float having overhanging surfaces, so inclined with respect to the surface 90 of the water as to produce at planing speed righting moments of sufficient intensity to neutralize the dynamic forces effective at such speed.

9. A marine structure comprising in combination a submerged hull, a streamline superstructure surmounting the hull and terminating in a hydroplane float, the lines of the superstructure merging into those of the float and hull, said float having overhanging 100 surfaces of such longitudinal and lateral inclination as to produce at high speeds righting moments of sufficient intensity to counteract the dynamic forces effective at such speeds.

105

10. A marine structure comprising in combination, a submerged hull, and a surmounting streamline superstructure terminating in a partially submerged hydroplane float, the lines of the superstructure merging into 110 those of the float and hull, said float having overhanging water bearing surfaces of such longitudinal and lateral inclination, or ranges of inclinations, as to produce at high speeds righting moments of sufficient intensity 115 to counteract the dynamic forces effective at such speeds.

11. A marine structure comprising in combination, a hull submerged to a predetermined depth, a streamline superstructure 120 surmounting the hull and terminating in a hydroplane float, the latter projecting well above water level, the lines of the superstructure merging into those of the float and hull, said float being formed to provide a 125 favorable angle to the water surface to produce at high speeds righting moments of sufficient intensity to counteract the dynamic forces effective at such speeds.

12. A marine structure comprising in com- 130

4
bination a submerged hull, a streamline superstructure surmounting the hull and terminating in a hydroplane float, which under normal conditions is disposed almost entirely 5 above water level, the lines of said superstructure merging into those of the float and hull, said float having overhanging surfaces of such inclination, transverse and longitudinal as to produce at planing speeds righting 10 moments of sufficient intensity to neutralize the dynamic forces effective at such speeds.

13. A marine structure comprising in combination a submerged hull, a surmounting 15 streamline superstructure terminating in a hydroplane float, the latter, under normal conditions, being almost entirely above water

level, said float having overhanging surfaces sloped with respect to the surface of the water to produce at planing speeds righting 20 moments of sufficient intensity to neutralize the dynamic forces effective at such speeds.

14. A marine structure comprising in combination a submerged hull, streamline superstructures surmounting the extremities of 25 the hull and terminating in a partially submerged hydroplane float, the floats having overhanging surfaces inclined at a favorable angle with respect to the surface of the water to produce at high speeds righting 30 moments of sufficient intensity to neutralize the dynamic forces effective at such speeds.

In testimony whereof I affix my signature.
REUBEN NOEL PERLEY.
